[57] CLAIM

The ornamental design for a mobile carrier, as shown and described.

DESCRIPTION

FIG. 1 is a perspective view of a mobile carrier showing my new design;

FIG. 2 is a side elevational view thereof;

FIG. 3 is an end elevational view thereof; and

FIG. 4 is an end elevational view thereof in folded condition.

The cord has been broken away in FIG. 2 for convenience of illustration, and the broken lines of FIG. 1 are for illustrative purposes only. The side and end not shown are mirror images of the side and end illustrated.

*Fig. 1.**Fig. 4.**Fig. 3.**Fig. 2.*
